DISPENSING MACHINE

Irven H. Wilsey, Chicago, Ill.

Application August 26, 1940, Serial No. 354,147

13 Claims. (Cl. 312—88)

The present invention pertains to dispensing machines for articles such as bottled or packaged goods.

By way of orientation in the art the presently disclosed machine may be considered as an improvement on that disclosed in my copending applications Serial No. 341,448, filed June 20, 1940, and Serial No. 345,288, filed July 13, 1940. In the earlier filed of said copending applications I have disclosed a bottle dispenser comprising a series of superimposed and separately revoluble carriers or trays of frusto conical form having bottle receiving pockets on their exteriors and from which the bottles are discharged by dogs, operative as an incident to carrier rotation, to strip passing bottles from the associated carriers. To revolve the carriers, they are driven from a single electric motor through overdrive connections, the carriers being normally latched against rotation and a predetermined carrier being unlatched for a desired step of rotation through the action of a coin operated electric control system. In the later filed one of said copending applications I have disclosed a somewhat similar dispensing machine embodying a novel type of selective control apparatus to permit rotation of a selected carrier from a series in which the several carriers are loaded with correspondingly different varieties of bottled goods. Though the machines described and claimed in said copending applications embody a number of important features other than those briefly indicated above, the foregoing will suffice in ascertaining the relation of the improvements herein disclosed and which accord with the present invention.

One object of the present invention is to provide a plural carrier dispensing machine of the type utilizing a single drive motor for a whole series of carriers, in which a novel mechanical interconnecting arrangement is utilized for accomplishing rotation of successive loaded carriers, as distinguished from the utilization of an electrical control system for such purpose as disclosed in my prior applications referred to above.

Another object is to provide a dispensing machine embodying a series of rotatable carriers together with a novel arrangement for coupling them together so that the drive is transmitted from a terminal one of the series through successive ones in the series to rotate them successively and through predetermined angular distances for each.

Another object is to provide such a dispensing machine embodying a novel arrangement for ini-

tiating a sequential step-by-step rotation beginning with any desired carrier in the mechanically interconnected series of carriers.

Still another object is to provide a dispensing machine of the type indicated, embodying a drive arrangement such that a series of carriers can be revolved one after another in sequence and in which the sequence may be caused to progress in one direction or the other through the series, as desired, but with the direction of rotation in either case the same.

Further objects and advantages of the invention will become apparent as the following description proceeds, taken in connection with the accompanying drawings in which:

Figure 1 is a general perspective view of a dispensing machine embodying the present invention.

Fig. 2 is an enlarged transverse sectional view taken substantially along the line 2—2 in Fig. 1.

Fig. 3 is a fragmentary side elevation of certain of the article-carriers of the machine, showing particularly the lost-motion type mechanical interconnecting means therebetween.

Fig. 4 is a vertical sectional view taken substantially along the line 4—4 in Fig. 2.

Fig. 5 is an enlarged detailed side elevation of the step-defining means for the article-carriers.

Fig. 6 is a plan view of the apparatus shown in Fig. 5.

Fig. 7 is an enlarged detail sectional view taken substantially along the line 7—7 in Fig. 2, showing the delivery apparatus for stripping the bottles from one of the carriers.

Figs. 8 and 9 are detail stop motion views, showing in end elevation one of the stripper dogs and adjacent carrier structure.

Figs. 10 and 11 are diagrammatic views showing the interrelation of the carrier lost-motion connection elements under different conditions of operation.

Fig. 12 is a wiring diagram of the electric control system for the machine.

Simply by way of exemplification, the invention has been disclosed herein as embodied in a machine especially designed for the dispensing of refrigerated bottled drinks. This particular illustrative form has been chosen because in some of its more limited aspects the invention has particularly to do with that class of machine. In its broader aspects, however, the invention is, as will be readily apparent to those skilled in the art, applicable to my other type of dispensing machines. Consequently, even though the par-

ticular form of the machine shown has been described in some detail herein, there is no intention to limit the invention to such embodiment but, on the other hand, I intend to cover all modifications and alternative constructions falling within the spirit and scope of the invention as expressed in the appended claims.

Upon reference to Fig. 1 it will be seen that the dispensing machine illustrated therein comprises an upright cabinet 10 of square cross section, resembling in general outline and construction the familiar refrigerator cabinet. Within this cabinet in a compartment 12 is housed a bottle storage and feed apparatus hereinafter described. In brief, bottled drinks are loaded within the cabinet and cooled by a suitable refrigerating system incorporated in the cabinet structure and including a refrigerant evaporator coil 11 (Fig. 4) supplied with refrigerant from a suitable compressor-condenser unit (not shown) housed in the lower portion of the cabinet and suitably controlled to maintain uniformly a desired temperature within the cabinet compartment 12 (Figs. 2 and 4). A purchaser inserts a coin or other check in the coin box 13 (Fig. 1) whereupon a chilled bottled drink is automatically delivered to him in the pocket 14 at the lower end of a delivery housing 15.

The cabinet 10 itself is shown as being of more or less conventional form for refrigerators. It comprises inner and outer steel shells 16, 17 separated by heat insulation 18 (Figs. 2 and 4) to define an inner heat insulated compartment 12, the front of which is closed by a pair of hinged heat insulated doors 19, 20 (Fig. 1). These doors are customarily locked so that they can only be opened by the proprietor. The bottle storage and feed apparatus within the compartment 12 is adapted to receive and store bottles *b* in the same general configuration as the machine described and claimed in my copending application Serial No. 341,448 referred to above. In common with the machine illustrated in said copending application, the presently disclosed one is designed to receive the bottles in a series of generally conical groups, each group being seated on one of a series of revoluble carriers, and the carriers being nested down one over the other. By virtue of this arrangement a maximum storage capacity is achieved. In the presently disclosed machine, however, a distinctly new and different arrangement is provided for revolving the carriers. Before proceeding to this latter point, however, the construction of the individual carriers will be described.

The bottles *b* are seated on a plurality of revoluble carriers any number of which may be provided, four being shown herein (Fig. 4) and designated as 21 to 24. The two intermediate carriers in the series, 22 and 23, are identical in construction. Each comprises a sheet metal hood 25 of frusto conical shape fixed to a complementally shaped peripheral flange on a central disk shaped spider 26. The spiders 26 are integral with hubs 27. Bottle receiving pockets are formed in an annular series about the exterior of the hoods 25 (see Fig. 2) by a plurality of V-shaped sheet metal barrier strips 28 welded or otherwise rigidly secured to the surface of the hoods. The lower ends of the legs of adjacent strips 28 are joined by transverse metal strips 28^a which form the bottoms of the pockets (see also Fig. 3). The other or terminal carriers 21 and 24 of the series are of substantially the same

construction as the intermediate carriers except for their hubs. Thus the upper terminal carrier 21 has an upwardly projecting hub 27^a on it and to the upper end of which is fixed a sprocket wheel 29. Similarly, the lower terminal carrier 24 has a short hub 27^b bolted to a coaxial sleeve 30 having a sprocket wheel 31 fixed to its lower portion.

The series of carriers 21 to 24 are revolvably supported in predetermined vertically spaced relation on a stationary upright shaft 32 (Fig. 4). This shaft is fixed to the upper and lower walls of the compartment 12 by suitable brackets 33, 34. Collars 35, pinned to the shaft 32, support the three upper carriers 21 to 23, while the sleeve 30, fixed to the lower carrier 24, is arranged with its lower end resting on the complementary upper end of the lower bracket 34.

Step-by-step rotation of the carriers 21 to 24 (by a drive mechanism described below) past corresponding delivery stations is utilized to strip successive bottles *b* from the carriers. For this purpose dog mechanisms substantially like those described and claimed in my copending application Serial No. 341,448 referred to above are provided. For present purposes it is sufficient to note that a dog 36 (Figs. 2 and 7) in the form of an offset arm on the end of a bar 37 is provided for each of the carriers. The dogs 36 project upwardly into what amounts to an annular slot or groove in the bottom of the corresponding carrier. For this purpose each of the barrier strips 27 is notched, as indicated, at 38 and at a point below the peripheral edge of the adjacent carrier hood 25. Consequently, the dog 36 passes through the lower portion of successive ones of the pockets as the carrier rotates, and, as the dog moves into each pocket, it raises the bottle therein (in moving from the position of Fig. 8 to that of Fig. 9) so that the lower end of the bottle is freed from the abutment strip 28^a at the bottom of the pocket. The bottle, thus lifted, is free to slide by gravity off of the inclined surface of the carrier. Each of the dog bars 37 is mounted for pivotal movement about its longitudinal axis in a bracket 39 (Figs. 2 and 7) fixed to an upright 40 adjacent the front of the compartment 12. The ends of the bars 37 opposite the dogs 36 have offset end portions 41 engaged by torsion springs 42 which also engage the adjacent bracket arms. These torsion springs urge the bars 37 to rotate counterclockwise (as viewed in Fig. 7) thus tending to draw the dogs 36 down out of operative engagement with the bottles on the associated carriers. The cabinet door 20 is arranged to abut against the offset bar ends 41, when the door is in its closed position, thus forcing the dogs 36 up into operative position. Whenever the door 20 is opened, however, the dogs 36 are automatically retracted by the action of the springs 42.

Bottles *b* stripped from the various carriers 21 to 24 by the dogs 36, in the manner described above, are received in the delivery housing 15 (Figs. 1 and 7). This delivery housing is made of sheet metal, being rectangular in cross section and its side walls project into a complementally shaped elongated slot in the cabinet door 19 (see Fig. 2).

The inner portion of the housing 15 has inclined partitions or slides 43 fixed therein and aligned with corresponding ones of the carriers. As the bottles *b* slip down off of the carriers they move on down these slides 43 and over the lower front edges of the latter so that they pass down

the housing or chute 15 and are finally received in the cup 14 which forms the lower terminus of the housing. The inner surfaces of the housing 15 and its slides 43 are preferably covered with fluted rubber mats 44 (Fig. 7) so as to safely limit the speed of sliding movement of the bottles.

In order to effect the necessary rotation of successive ones of the carriers to deliver bottles from them as described above, a novel interrelated drive system has been provided in accordance with one aspect of the present invention. In brief, the instant drive system is such that either one or the other of the two terminal carriers 21 or 24 in the series can be power driven, each in the same direction, from a single electric motor. The arrangement is, furthermore, such that the drive is transmitted, through the carriers themselves, to one after another of them beginning with the terminal carrier which is selected for power drive and progressing on through the series to the other end. Also, the arrangement is such that each carrier is revolved into a predetermined angular position relative to the next adjacent carrier before it becomes effective to initiate revolving movement of such adjacent carrier. The rotation of each of the carriers is effected in a step-by-step manner, each step being of sufficient distance to bring a fresh bottle into operative engagement with the associated stripper dog, and each step of movement for the various carriers is initiated by actuation of a coin or check controlled device.

As to the alternatively available drive connections to the two terminal carriers 21 and 24, it will be observed upon reference to Fig. 4 that an electric driving motor 45 is provided. This motor is connected to a sprocket 46 through a speed reduction gearing in a housing 47 and the sprocket 46 is, in turn, connected by an endless roller chain 48 with a second sprocket 49. The latter sprocket is fixed on a vertical drive shaft 50 supported for free rotation and limited endwise movement by bearings 51 in the rear right hand corner of the compartment 12 (see also Fig. 2).

The drive shaft 50 is shiftable endwise from the mid or neutral position shown, either up or down, by means of a shifter fork 52 engaged with a collar 53 fast on the shaft and pivotally mounted on a bracket 54 on the side wall of the compartment. A sector 55 fast on the shifter fork has an arcuate slot 56 in it through which projects a bolt 57 having a wing nut 58 on it and by means of which the shifter fork 52 may be releasably retained in either the mid or neutral position shown or in its alternatively available upper or lower positions. Clutch mechanisms, designated generally as 58 and 59 (Fig. 4) are arranged at the upper and lower end portions of the shaft 50, respectively, the clutch 58 being arranged for engagement when the shaft is shifted downward and the clutch 59 to be engaged when the shaft is shifted upward.

The upper clutch mechanism 58 comprises a collar 60 loosely encircling the shaft 50 and mounted for free rotation on a bracket 61. Slots or interdental spaces 62 in the upper edge of the collar 60 are arranged to receive a cooperating cross pin 63 on the shaft 50. Similarly, the lower clutch 59 includes a collar 64 freely revoluble in a bracket 65 and having notches 66 arranged to receive a cross pin 67 on the shaft 50. The upper clutch collar 60 has fixed to it a sprocket 68 over which is trained an endless

roller chain 69 connecting it to the sprocket 29 fast on the hub of the upper carrier 21. Similarly, the lower clutch collar 64 has fast on it a sprocket 70 over which is trained an endless roller chain 71 that connects it to the sprocket 31 on the lower carrier's sleeve 30. It will thus be seen that when the wing nut 58 is loosened and the shifter fork 52 swung upward to engage the clutch 59 that the motor 45 is connected in driving relation with the upper terminal carrier 21. In both cases the unidirectional motor 45 revolves the terminal carrier to which it is connected in the same direction since no reversing gear mechanism is interposed.

To form lost motion connections between adjacent ones of the carriers so that, as pointed out generally above, they can be driven from either one of the terminal carriers in the series, mating projections are provided on them. Thus each of the carriers 24, 23 and 22 has on it an upstanding projection 72 in the form of an integral extension on one of its barrier strips 28 (Figs. 3 and 4). Cooperating with these projections 72 are L-shaped lugs or projections 73 fixed on the lower sides of the carriers 21, 22 and 23. A similar bottom projection 73 is also provided on the lower carrier 24 for engagement with the actuator for a stop switch as hereinafter described. With such an arrangement, when one of the carriers is revolved to a position in which one of the connecting projections on its abuts against the complementary connecting projections on the next adjacent carrier, the latter is thereafter revolved with the first mentioned carrier.

An important characteristic of the drive arrangement described above is that, after one of the terminal carriers has been revolved sufficiently so that all of the other carriers are finally connected in driven relation with it, then the other terminal carrier can subsequently be made the driver and revolved in identically the same direction in which it was turned as the tail-end member of the series before, to effect a successive "picking up" of the carriers in the series but progressing in the opposite direction through the series. To make this action plain, reference may be made to the diagrammatic views in Figs. 10 and 11 in which the various carriers have been indicated by concentric circles suitably numbered and their interengaging projections 72, 73 shown. Assuming that the carriers are initially positioned with their interengaging projections 72, 73 located as shown in Fig. 10 in what may be termed an "unwound" position, then the driving of the carriers may be initiated by revolving the lower terminal carrier 24 in a clockwise direction. For this purpose the clutch 59 is, of course, engaged to connect the motor 45 to the lower carrier 24. After the lower carrier makes substantially one full revolution its projection 72 engages the right hand face of the complementary projection 73 on the next carrier 23. Thereafter, during the next succeeding revolution of the terminal carrier 24 the adjacent carrier 23 is carried with it. Similarly, in the next revolution of the carrier 24 both the carriers 22 and 23 are carried with it. This picking up of an additional carrier continues throughout the series until it has, so to speak, been "wound up", coming to rest with the projections 72, 73 located in the relative positions shown in Fig. 11. Thereafter, if the clutch 59 is disengaged and the clutch 58 engaged, in the manner heretofore described, to connect the drive motor 45 to the

other or upper terminal carrier 21 the latter will again be revolved clockwise from the position shown in Fig. 11. Accordingly, the projection 73 on the carrier 21 moves away from the coacting projection 72 on the next carrier 22, the carrier 21 makes substantially a full revolution, and at the end of this first revolution the projection 73 on the carrier 21 contacts the right hand face of the projection 72 on the carrier 22. During the next succeeding revolution the carrier 22 is carried along with the carrier 21 and during each succeeding revolution another carrier is picked up. This continues until the whole series of carriers is again "unwound," coming to rest in the initial position shown in Fig. 10. It will be observed that during this operation each successive carrier makes substantially a full revolution before the next succeeding carrier is connected in driven relation with the power actuated terminal carrier. More precisely, each carrier revolves, under the circumstances noted, through 360 degrees less the width of the interconnecting projection on the next adjacent carrier.

The feature of unidirectional rotation of the carriers for either "winding" or "unwinding" of the series is highly desirable in that it insures that in either case the carriers will revolve in the same direction with respect to the stripper mechanisms which operate to release the bottles from them. This simplifies the construction of the stripper mechanisms since they need be designed to accommodate only one direction of rotation of the associated carrier. Additionally, a unidirectional drive motor without any reversing gearing can be used, as distinguished from a more expensive reversing type of drive.

To accomplish a step-by-step type of carrier rotation during dispensing, as distinguished from a continuous rotation, a step-defining mechanism designated generally at 75 is utilized (Figs. 4, 5 and 6). This mechanism comprises a pair of peripherally notched disks 76, 77 rigidly fixed to the drive shaft 50. Each disk has a notch in it corresponding to one of the bottle-receiving pockets on the carriers. The disks are, however, arranged with the notches on one offset slightly in an angular sense with respect to the corresponding notches on the other. This offset is sufficient to accommodate the difference in stopping position required when the series of carriers is being driven from the respective upper or lower terminal carriers, i. e. "wound" or "unwound." A latch mechanism, including a sector shaped latch plate 78 pivoted on a bracket 79 is arranged to engage one or the other of the disks 76, 77, depending upon which of the two is moved into registry with it by the endwise shifting of the shaft 50. Thus, when the shaft 50 is shifted downward to engage the upper clutch 58 the notched disk 76 is aligned with the nose of the latch plate 78. On the other hand, when the shaft 50 is shifted upward to engage the lower clutch 59, the other notched disk 77 is positioned for engagement with the latch plate 78. A tension spring 80 yieldably urges the latch plate 78 into engagement with the periphery of the aligned one of the alternatively available disks, while a solenoid 81, having its armature 82 pivotally connected with the latch plate, serves, when energized, to retract the latch.

Associated with the latch mechanism described above is a "motor" switch 83 comprising a pair

of normally open switch contacts carried by yieldable spring fingers 84, 85 mounted in insulated relation to each other. The lower spring finger 85 is disposed in the path of the heel of the latch plate 78 so that when the latter is retracted the finger 85 will be pushed upward, closing the switch. Thus, if the solenoid 81 is momentarily energized to withdraw the latch plate 78 so that the cooperating one of the disks 76, 77 is freed for rotation, the switch 83 will be simultaneously closed to start the motor 45 so that the shaft 50 starts to revolve. This moves the notch, in which the latch plate 78 was previously entered, out of registry with the latch plate. Therefore, upon subsequent deenergization of the solenoid 81 the nose of the latch rides loosely along the periphery of the revolving disk. When the next notch on the disk reaches the latch plate, however, the latter snaps into this notch, thereby opening the switch 83 to stop the motor and also positively arresting further rotation of the drive shaft 50. In this way each step of rotation for the carriers can be initiated simply by a momentary energization of the single solenoid 81.

If it is desired to revolve the carriers continuously, rather than step by step, it is necessary, in general, to energize the solenoid 81 substantially continuously so that the latch plate 78 will be maintained in retracted position and the motor 45 continuously energized by the closed switch 83. Such continuous rotation of the carriers is desirable during refilling or restocking of the machine and a manually operable "refill" switch 86 (Fig. 2) is mounted within the cabinet and connected in a manner hereinafter described to effect the necessary continuous energization of the solenoid 81.

In some instances it is desirable to arrest further rotation of the carriers 21 to 24 after the movement thereof has progressed through only a part of the total available series of steps. To this end an "empty" switch 87 (Figs. 2 and 4) is provided within the cabinet. This switch has a pair of normally open contacts and is arranged to be closed by an arm 88 fixed to an upright shaft 89. This shaft 89 is journaled for oscillation by a pair of bearings 90 and has on it an arm 91 projecting from a collar 92 which may be releasably held in any desired position of adjustment longitudinally of the shaft by a thumb screw 93. In the position shown in Fig. 4 the arm 91 is arranged to be contacted by the projection 73 on the uppermost carrier 21. When contacted by this projection the arm 91 is swung counterclockwise (as viewed in Fig. 3) thereby causing the arm 88 to close the "empty" switch 87. Through the medium of circuits described below, closure of this switch serves to stop the drive motor 45. In a similar manner the arm 91 can be positioned along the length of the shaft 89 to be contacted by the projections 73 on any of the other carriers so that they too can serve to stop the drive motor 45. Incidentally, it should be noted at this point that again the unidirectional rotation of the carriers serves to simplify this actuating mechanism for the "empty" switch 87 since such actuating mechanism need be arranged for operation only in response to rotation of the associated carriers in one direction.

Turning now to the electric control system for the machine (Fig. 12), most of the elements will by now be familiar, including the "refill" switch 86, the adjustable "empty" switch 87, the

"motor" switch 83, the solenoid or "carrier release coil" 81 and, of course, the motor 45 itself. Additionally, the system shown includes a coin switch 95, a coin lockout coil 96, and a lockout relay 97 having an actuating winding 98 and a pair of normally open contacts 99. Current is furnished for the system from supply lines L₁, L₂ which may be plugged into any suitable source of current such, for example, as an ordinary lighting system. The coin switch 95 is disposed in the coin box 13 (see Fig. 1) being of well known form, and is arranged to be momentarily closed upon dropping a coin into the coin box. The lockout coil 96 acts, in accordance with usual practice in such coin boxes, when energized, to divert the entering coin from the coin receiver and permit it to pass on out into a return cup 13a on the coin box. When the lockout coil 96 is deenergized, however, the inserted coin is free to pass into the usual coin receptacle within the box.

As to the operation of the machine it will first of all be assumed that all of the carriers 21 to 24 are fully loaded and disposed initially with their coating projection 72, 73 positioned relative to each other in the "unwound" position indicated in Fig. 10. In such case the proprietor, prior to locking the doors 19, 20, reaches into the compartment 12 and shifts the drive shaft 50 upward so as to engage the lower clutch 59 and disengage the upper clutch 58. The "refill" switch 86 is, of course, open and it will further be assumed that the actuating arm 91 for the "empty" switch 87 is positioned as shown in Fig. 4 or, in other words, located so as to be actuated by the projection 73 on the uppermost carrier 21 after the latter has turned through a full revolution from its initial position. Having thus initially set up the machine the proprietor closes and locks the doors 19 and 20. Incidentally, it should be noted that the closing of the door 20 thrusts the stripper dogs 36 up into operative position.

After the machine has been initially conditioned as described above, the insertion of a coin into the coin box 13 causes the coin switch 95 to be momentarily closed. Closure of this coin switch effects a corresponding momentary energization of the solenoid 81 (through a circuit L₁—95—81—L₂) so that the latch plate 78 is momentarily withdrawn from engagement with the notched disk 77. Withdrawal of the latch plate also closes the motor switch 83 starting the drive motor 45. As a consequence, the lower terminal carrier 24 is advanced one step, with the result that a bottle is stripped from it by its co-operating dog 36 and the bottle thus removed slides down the delivery housing 15 into the pocket 14 where it can be picked up by the purchaser. At the end of this one step of advance the nose of the latch plate 78 drops into the next notch on the disk 77, thereby positively arresting further rotation of the carrier 24 and also opening the switch 78 to deenergize the drive motor.

The operation described above is repeated, as successive coins are dropped into the box 13 until the carrier 24 has been stepped around through substantially one full revolution and at which point its contents is exhausted. Thereupon its interconnecting projection 72 comes into abutting engagement with the mating projection 73 on the next carrier 23. Accordingly, the carrier 23 is stepped around with the carrier 24 during the succeeding revolution of the latter,

the steps of which are caused by dropping successive coins into the box 13. Such step-by-step rotation of successive carriers continues through the series until finally the last carrier 21 has been turned through a full revolution. Thereupon the projection 73 on this last carrier strikes the arm 91, turning the shaft 89 and closing the "empty" switch 87. Closure of this switch 87 completes a circuit for the energizing winding 98 of the lockout relay 97 so that the latter closes its contacts 99 which, in turn, complete an energizing circuit for the lockout coil 96. As a result, any coins thereafter dropped into the coin box 13 will simply be returned to the prospective purchaser, indicating that the machine is empty.

Machines of the character described are commonly serviced by a driver who goes daily over a route including a number of such machines. The driver or service man collects the money from each machine and replenishes the stock of bottles. More often than not he will find that only part of the stock of bottles has been sold from a machine when he arrives to refill it. The machine herein disclosed is particularly adapted to meet such a contingency in that it can be readily set up to dispense first the bottles which are already in the machine, and, hence, already cold, and thereafter dispense the newly stocked bottles, which will have had an opportunity to be cooled in the meantime. For example, the service man may find that all of the bottles have been sold from carriers 24 and 23 but that carriers 21 and 22 are still full. Upon discovering this condition when he opens the cabinet doors 19, 20 the service man closes the refill switch 86. Closure of this switch 86 energizes the solenoid 81 continuously so that the motor 45 is energized to revolve the carriers around and around without any pause or steps. As the empty carriers 23 and 24 revolve the operator slides fresh bottles, neck foremost, into the pockets to refill these carriers. During this revolving movement the series of carriers is fully "wound up" so that all of the interengaging projections 72, 73 are engaged in the manner shown in Fig. 11. After the carriers 23, 24 have thus been refilled, the operator opens the "refill" switch 86, stopping the motor 45. He then reaches in and loosens the wing nut 58 and shifts the fork 52 so as to disengage the previously engaged lower clutch 59 and engage the upper clutch 58. The service man also loosens the thumb screw 93 and shifts the "empty" switch's actuator arm 91 down for engagement with the projection 73 on the lowermost carrier 24. He then closes and locks the cabinet doors 19, 20 and the machine is thereby conditioned for a subsequent "unwinding" cycle of dispensing. In this subsequent dispensing operation the drive is derived through the upper terminal carrier 21 so that its load is discharged first and then the load of bottles on the carrier 22 and so on down through the series. In this way the colder bottles on the carriers 21 and 22 are dispensed first.

In some instances the service man may find that he does not have on hand sufficient bottles to fill all of the carries and in such case the actuator arm 91 for the "empty" switch 87 can be set at an appropriate point to stop the machine after all of the available fractional load of bottles has been dispensed. In this connection it should be noted that the actuator arm 91 can be set for engagement with the projection 73 on any one of the carriers, thereby stopping the dispensing cycle when the selected carrier

reaches the angular position in which its projection 73 contacts the actuator arm 91 so that the carriers which follow it in the series are, in effect, cut out of service. Similarly, the condition can be accommodated in which only a portion of the pockets on one of the carriers are filled with bottles. In such case the partially filled carrier is revolved by hand, during the re-loading operation, so that all of its empty pockets have been moved past the associated stripper dog 36. Thereafter, this carrier will be stepped around by the drive mechanism in the usual way to dispense the fractional load of bottles on it and at the completion of such dispensing of the bottles one of the projections on it will either pick up the next adjacent carrier to revolve the latter or else strike the actuator arm 91 for the "empty" switch, as the case may be. The free rotational mounting of the carriers fully accommodates such manual adjustment of the initial angular positions of the various carriers.

I claim as my invention:

1. In a dispensing machine, the combination of a series of revoluble article-carriers all journaled for rotation about a common axis, power actuated means for alternatively revolving one or the other of the two terminal carriers of the series though in each instance in the same direction, and means for causing successive carriers in the series to revolve in unison with a carrier next adjacent to it upon a predetermined angular positioning of such adjacent carriers relative to each other beginning with the carrier adjacent the one of said terminal carriers which is driven by said power actuated means and progressing through the series in a direction away from such power driven terminal carrier.

2. In a dispensing machine, the combination of a series of carriers all disposed for rotation about a common axis, means including a projection on each carrier arranged to abut against a mating projection on each next adjacent carrier for connecting adjacent ones of said carriers for rotation in unison when such adjacent carriers are revolved relative to each other to bring their mating projections into abutting engagement in either of two relative angular positions of the carriers, such positions being spaced apart 360 degrees less the thickness of one of said projections, first power actuated means for revolving one of the terminal carriers of the series in one direction to bring said projections on successive ones of said carriers in the series, beginning with said one terminal carrier, into engagement with the mating projection on the next adjacent carrier in the series until all of said carriers are revolving in unison in said one direction, and a second power actuated means for alternatively revolving the other terminal carrier of said series in said same one direction to bring successive ones of said carriers, beginning with said other terminal carrier, into engagement with the mating projections on the next adjacent carrier in the series until all of said carriers are again revolving in unison in said one direction though driven from said other terminal carrier.

3. In a dispensing machine, the combination of a series of revoluble carriers each adapted to receive a plurality of articles to be dispensed, discharge means for delivering successive articles from associated ones of said carriers as an incident to rotation thereof, power actuated drive means for said carriers, check-controlled means for initiating successive incremental operations

of said drive means, each sufficient to move a carrier far enough to effect the delivery of an article from it by said discharge means, and presettable control means for conditioning said drive means to revolve said carriers with rotation of individual carriers initiated one after another alternatively in either a first predetermined order of the carriers or in a second predetermined order which is the reverse of the first.

4. In a dispensing machine, the combination of a series of revoluble article-carriers all journaled for rotation about a common axis, power actuated means for alternatively revolving one or the other of the two terminal carriers of the series though in each instance in the same direction, connecting means for causing successive carriers in the series to revolve in unison with a carrier next adjacent to it upon a predetermined angular positioning of such adjacent carriers relative to each other beginning with the carrier adjacent the one of said terminal carriers which is driven by said power actuated means and progressing in the series in a direction away from such power driven terminal carrier, check-controlled means operable upon each actuation thereof to render said power actuated means operative to advance the terminal carrier associated therewith by said connecting means a predetermined step, and discharge means associated with said carriers for delivering therefrom an article upon each step of advance thereof.

5. In a dispensing machine, the combination of a series of revoluble article-carriers all journaled for rotation about a common axis, power actuated means for alternatively revolving one or the other of the two terminal carriers of the series though in each instance in the same direction, presettable connecting means for causing successive carriers in the series to revolve in unison with a carrier next adjacent to it upon a predetermined angular positioning of such adjacent carriers relative to each other beginning with the carrier adjacent the one of said terminal carriers which is driven by said power actuated means and progressing in the series in a direction away from such power driven terminal carrier, a pair of peripheral notched disks arranged to be revolved in unison with respective ones of said terminal carriers, a withdrawable latch, electromagnetic means operable when energized to withdraw said latch, means operable in response to the setting of said presettable connecting means for shifting the corresponding one of said disks into operative relation with said latch, said latch being normally urged toward the notched periphery of the disk operatively associated with it, either of said disks being operative when held by engagement of said latch with a notch therein to prevent rotation of said carriers, check-controlled means for momentarily energizing said electromagnetic means to withdraw said latch and free the associated disk, and means for rendering said power actuated means operative so long as said latch is withdrawn.

6. In a dispensing machine, the combination of a drive shaft, means supporting said shaft for free rotation and for limited axial shifting movement, an electric drive motor for said shaft, a series of article-carriers all journaled for rotation about a common axis, means including first and second clutches alternatively engageable upon shifting of said shaft endwise to respective limit positions for connecting said shaft in driving relation with respective terminal

carriers of said series, means for causing successive carriers in the series to revolve in unison with a carrier next adjacent to it upon a predetermined angular positioning of such adjacent carriers relative to each other beginning with the one of said terminal carriers which is connected by its clutch to be driven by said shaft and progressing through the series in a direction away from such driven terminal carrier, and means including a latch mechanism stationarily supported adjacent said shaft and a pair of peripherally notched disks fixed to said shaft and adapted to be alternatively positioned for engagement with the latch in the respective limit positions of endwise shifting of said shaft for defining incremental steps of revolution for the shaft.

7. In a dispensing machine, the combination of a plurality of revolvably mounted carriers, each adapted to receive an annular series of articles to be dispensed, discharge means for delivering articles presented successively thereto by said carriers as an incident to the latter's rotation, means including a single electric motor for revolving all of said carriers, a peripherally notched disk driven by said motor in unison with said carriers, a latch normally urged into engagement with said disk for holding the disk and motor against further rotation when the latch enters one of the disk's notches, electromagnetic means operable when energized to withdraw said latch, check-controlled means operable when actuated to momentarily energize said electromagnetic means, and means for energizing said motor whenever said latch is in withdrawn position.

8. In a dispensing machine, the combination of a series of carriers all mounted for free rotation about a common axis and each being adapted to receive an annularly disposed series of articles to be dispensed, a plurality of discharge means, one for each carrier, for stripping successive articles therefrom in the course of carrier rotation, power actuated means for revolving one of the terminal carriers in the series, means rendered operable upon the completion of a predetermined rotation of said one terminal carrier relative to the next adjacent carrier to connect the latter in driven relation with said one terminal carrier, means for connecting each successive carrier in the series, progressing from said one terminal carrier toward the other end of the series, in driven relation with the carrier ahead of it in the series after the latter has revolved to a predetermined angular position relative to the succeeding carrier, check-controlled means operative upon each actuation thereof to render said power actuated means operative to advance said one terminal carrier a step, each step of carrier advance being sufficient to present the next successive article thereon to the associated discharge means, and means available at will as an alternative to said check-controlled means for rendering said power actuated means operative to revolve said terminal carrier continuously rather than with a step-by-step motion.

9. In a dispensing machine, the combination of a series of carriers all mounted for free rotation about a common axis and each being adapted to receive an annularly disposed series of articles to be dispensed, a plurality of discharge means, one for each carrier, for stripping successive articles therefrom in the course of carrier rotation, power actuated means for re-

volving one of the terminal carriers in the series, means rendered operable upon the completion of a predetermined rotation of said one terminal carrier relative to the next adjacent carrier to connect the latter in driven relation with said one terminal carrier, means for connecting each successive carrier in the series, progressing from said one terminal carrier toward the other end of the series, in driven relation with the carrier ahead of it in the series after the latter has revolved to a predetermined angular position relative to the succeeding carrier, check-controlled means operative upon each actuation thereof to render said power actuated means operative to advance said one terminal carrier a step, each step of carrier advance being sufficient to present the next successive article thereon to the associated discharge means, and means presettable at will to disable said check-controlled means against causing said power actuated means to effect further carrier rotation when any desired carrier in the series reaches a predetermined angular position of advance.

10. In a dispensing machine, the combination of a series of carriers all mounted for free rotation about a common axis and each being adapted to receive an annularly disposed series of articles to be dispensed, a plurality of discharge means, one for each carrier, for stripping successive articles therefrom in the course of carrier rotation, power actuated means for revolving one of the terminal carriers in the series, means rendered operable upon the completion of a predetermined rotation of said one terminal carrier relative to the next adjacent carrier to connect the latter in driven relation with said one terminal carrier, means for connecting each successive carrier in the series, progressing from said one terminal carrier toward the other end of the series, in driven relation with the carrier ahead of it in the series after the latter has revolved to a predetermined angular position relative to the succeeding carrier, and said carriers all being manually positionable initially, in view of their free rotational mounting, to a desired initial angular position relative to the next adjacent carriers on each side of them in the series.

11. In a dispensing machine, the combination of a vertical shaft having a series of superimposed carriers freely journaled thereon at vertically spaced points, each of said carriers being of generally conical form nested down over the carrier next below it and each carrier having thereon means defining a series of article-receiving pockets about its exterior conical surface, discharge means cooperating with the respective carriers for releasing articles from successive pockets thereon as the carriers are revolved past said discharge means to permit the released articles to slide outward and downward from the conical carrier surface by gravity for delivery, power actuated means for revolving one of the two terminal carriers in the series, and each of said carriers having a projection thereon arranged to engage a complementary projection on the next adjacent carrier in the series when revolved into a predetermined angular position relative to such next adjacent carrier whereby the whole series of carriers is revolved one after another from said power driven terminal carrier.

12. In a dispensing machine, the combination of a series of carriers mounted for independent rotation about a common axis and each adapted

to receive an annularly disposed series of articles to be dispensed, a plurality of discharge means, one for each carrier, for stripping successive articles therefrom in the course of rotation of the associated carrier, power actuated means for revolving one of the terminal carriers in the series, and means forming mechanical lost-motion connections between the adjacent carriers in the series for causing successive carriers to be revolved from said one terminal carrier after each successive carrier has been revolved to a predetermined angular position with relation to its next adjacent carrier.

13. In a dispensing machine, the combination of a vertical shaft, means journaling each of a series of article-carriers for free rotation on said shaft at vertically spaced points, each of said carriers comprising a sheet metal hood of truncated conical form and each being nested down over the carrier next below it, each carrier having thereon a plurality of upright barrier strips extending up toward the carrier cen-

5 ter and defining an annular series of article-receiving pockets about the exterior of the hood's truncated conical surface, discharge means cooperating with the respective carriers for releasing articles from successive pockets thereon as the carriers are revolved past said discharge means to permit the released articles to slide outward and downward from the truncated conical hood surface by gravity for delivery, power actuated means for revolving one of the two terminal carriers in the series on said shaft, and each of said carriers except the uppermost one having a projection thereon integral with one of said barrier strips and extending upwardly to engage a complementary downwardly extending projection on the next adjacent carrier in the series when revolved into a predetermined angular position relative to such next adjacent carrier, whereby the whole series of carriers may be revolved one after another from the power driven terminal carrier.

IRVEN H. WILSEY.
